(57) **CLAIM**

The ornamental design for a multi-section portable electronic torch, as shown and described.

DESCRIPTION

FIG. 1 is a top to bottom perspective view of a multi-section portable electronic torch showing our new design, where the multi-section portable electronic torch includes a first textured handle;

FIG. 2 is bottom to top perspective view thereof;
FIG. 3 is a front side view thereof;
FIG. 4 is a back side view thereof;
FIG. 5 is a left side view thereof;
FIG. 6 is a right side view thereof;
FIG. 7 is a top view thereof;
FIG. 8 is a bottom view thereof;
FIG. 9 is a top to bottom perspective view of a first alternate configuration where the multi-section portable electronic torch includes a second textured handle;
FIG. 10 is a bottom to top perspective view of the first alternate configuration;
FIG. 11 is a front side view of the first alternate configuration;
FIG. 12 is a back side view of the first alternate configuration;
FIG. 13 is a left side view of the first alternate configuration;
FIG. 14 is a right side view of the first alternate configuration;
FIG. 15 is a top view of the first alternate configuration;
FIG. 16 is a bottom view of the first alternate configuration;
FIG. 17 is a top to bottom perspective view of a second alternate configuration, where the multi-section portable electronic torch includes a third textured handle;
FIG. 18 is a bottom to top perspective view of the second alternate configuration;
FIG. 19 is a front side view of the second alternate configuration;
FIG. 20 is a back side view of the second alternate configuration;
FIG. 21 is a left side view of the second alternate configuration;
FIG. 22 is a right side view of the second alternate configuration;
FIG. 23 is a top view of the second alternate configuration; and,
FIG. 24 is a bottom view of the second alternate configuration.
